UNITED STATES PATENT OFFICE

ISRAEL P. PEARLMAN, OF PROVIDENCE, RHODE ISLAND

DESIGN FOR A DISPLAY CABINET

Application filed January 30, 1929. Serial No. 29,842. Term of patent 14 years.

To all whom it may concern:

Be it known that ISRAEL P. PEARLMAN, a citizen in the United States, residing at Providence, of the county of Providence and State of Rhode Island, has invented a new, original, and ornamental Design for a Display Cabinet, of which the following is a specification, reference being had to the accompanying drawing, forming a part thereof.

Fig. 1 is a perspective view of a display cabinet embodying my new design.

Fig. 2 is a plan view thereof.

I claim:

The ornamental design for a display cabinet substantially as shown.

In testimony whereof I affix my signature.

ISRAEL P. PEARLMAN.
